UNITED STATES PATENT OFFICE.

EDWIN L. WHITE, OF BROOKLYN, NEW YORK.

DESIGN FOR A HANGER FOR LIGHT-TRANSMITTING BOWLS.

51,272.

Specification for Design.

Patented Sept. 11, 1917.

Application filed July 26, 1917. Serial No. 182,985. Term of patent 3½ years.

To all whom it may concern:

Be it known that I, EDWIN L. WHITE, a citizen of the United States, residing at the borough of Brooklyn, in the county of Kings, city and State of New York, have invented a new, original, and ornamental Design for a Hanger for Light-Transmitting Bowls, of which the following is a specification, reference being had to the accompanying drawings, forming part thereof.

The figure is a side elevation of a hanger for light transmitting bowls, showing my new design.

I claim.

The ornamental design for a hanger for light transmitting bowls, as shown.

EDWIN L. WHITE.
